CLAIM

The ornamental design for a cutting insert, as shown and described.

DESCRIPTION

3.1-3.8. Cutting inserts

FIG. 3.1 is a Front Perspective View of a cutting insert showing our new design;

FIG. 3.2 is a Rear Perspective View thereof;

FIG. 3.3 is a Top View thereof;

FIG. 3.4 is a Bottom View thereof;

FIG. 3.5 is a Front View thereof;

FIG. 3.6 is a Back View thereof;

FIG. 3.7 is a Left View thereof; and

FIG. 3.8 is a Right View thereof.

The broken lines depicting the remainder of the cutting insert show features that form no part of the claimed design.
